UNITED STATES PATENT OFFICE.

FREDERICK DIEHL, OF ELIZABETH, NEW JERSEY, ASSIGNOR TO THE SINGER MANUFACTURING COMPANY, OF ELIZABETH, NEW JERSEY, A CORPORATION OF NEW JERSEY.

LIGHTING ATTACHMENT FOR SEWING MACHINES.

Application filed March 5, 1921. Serial No. 449,968.

To all whom it may concern:

Be it known that I, FREDERICK DIEHL, a citizen of the United States, residing at Elizabeth, in the county of Union and State 5 of New Jersey, have invented certain new and useful Improvements in Lighting Attachments for Sewing Machines, of which the following is a specification, reference being had therein to the accompanying drawings.

This invention relates to sewing machine lighting attachments and has for an object to provide a lighting attachment which is simple in construction and inexpensive to 15 manufacture.

A further object of the invention is to provide a lighting attachment which may be readily mounted upon a sewing machine in such a manner and position as to effectively 20 illuminate the work being stitched without producing objectionable reflection of the light from the work and without casting objectionable shadows of machine parts on the work.

25 A further object of the invention is to provide a sewing machine lighting attachment which, when in position on the machine, will give an abundant distribution of the light without objectionable glare.

30 A further object of the invention is to provide a lighting attachment of the class described which will not be subjected to excessive or objectionable vibration when the sewing machine is in operation.

35 Still further, the invention has for an object to provide a lighting attachment which, when in working position on a sewing machine, will not interfere with and need not be shifted or manipulated by the operator to permit the dropping of the sewing machine head within the cavity of the usual drop-head stand, or with the placing of the cover of a portable hand-carrying case over the sewing head.

40 The objects of the invention are attained by mounting an electric lamp-socket carrying a lamp-bulb and reflector upon and closely adjacent a supporting element adapted for attachment to the sewing machine 45 gooseneck, preferably adjacent the bend of the latter, so that the lamp-bulb and its reflector will be supported horizontally closely in rear of and alongside the horizontal arm of the gooseneck at a position between the 50 needle-bar supporting head and the stand-

ard. The lamp-socket may conveniently be supported, as indicated, by mounting it upon and in close proximity to a cover-plate adapted to close the opening usually provided at the rear of the bracket-arm of a 60 sewing machine for access to the mechanism within the arm. The use of an elongated arm for extending the light toward the sewing point is to be avoided as such arm will permit objectionable vibration of the 65 light at the free end thereof and will cause the needle-bar head or other parts at the free end of the gooseneck to cast objectionable shadows. By mounting the lamp socket and bulb as described, they are permanently positioned horizontally closely in 70 rear of and alongside the horizontal arm of the sewing machine gooseneck at a position well to one side of the vertical plane through the line of feed of the machine, 75 whereby the light will shine upon the work obliquely from the operator's right, and the casting of objectionable shadows upon the work by the presser-bar, presser-foot, needle-bar supporting head or other parts carried 80 by the sewing machine gooseneck or bracket-arm, is avoided. Further, by so locating the light, objectionable reflection of the light from the work into the eyes of the operator 85 is avoided. Also, advantage is taken of the 90 bracket-arm as a shade to effectively shield the eyes of the operator from the glare of the lamp while permitting the use of a lamp reflector not so deep or so fully enveloping the lamp globe as to cause overheating or to 95 prevent a generous distribution of the light over the work.

In the accompanying drawings, Fig. 1 is a perspective view of my improved lighting attachment as mounted upon a sewing machine. Fig. 2 is a fragmentary top plan view of the same. Fig. 3 is a perspective view of the special cover-plate used as a support for the light.

In the accompanying drawings showing 100 one embodiment of the invention, a sewing machine head of usual construction is illustrated as mounted upon a portable base 1. The sewing machine frame comprises a flat bed 2 from which rises the hollow bracket- 105 arm or goose-neck including the standard 3 and horizontal member 3' terminating in the head 4 in which are slidably mounted the usual presser-bar 5 and reciprocating needle-bar 6 carrying, respectively, the 110

presser-foot 7 and needle 8. Cooperating with the presser-foot 7 to feed the work is the usual feed-dog 9. The needle 8 cooperates with the usual loop-taker below the bed 2 to form stitches. Machines of this type are usually driven by a suitable motor attachment which has been omitted from the illustration since it forms no part of the present invention. The sewing machine 10 may, of course, be supported and driven in any desired manner.

The hollow bracket-arm 3, 3' of a sewing machine of the type referred to is usually provided with an opening 10 permitting access to the working parts mounted within the arm. This opening is customarily located at the rearward side of the bracket-arm and substantially at the bend of the latter.

The present lighting attachment, in the 20 embodiment illustrated, comprises a support in the form of a cover-plate 11 shaped to close the opening 10 and formed with an upper screw-hole 12 to receive the usual cover-plate thumb-screw 13. The electric lighting socket 14 is non-adjustably secured to its support 11, in close proximity to the latter, preferably by providing the cover-plate with a projection which may be in the form of an integral ear 15 bent rearwardly so as 25 to stand in a vertical plane perpendicular to the plane of the plate 11 proper. The ear 15 may be formed with an aperture 16 to admit the nipple 17 which is threaded into the cap 18 of the usual lighting socket 14. 30 The nipple 17 is preferably threaded at 19 to receive the insulating bushing 20 for the lamp cord 21.

The socket 14 receives the lamp bulb 22, 40 preferably of the elongated tubular or cylindrical type and supports a suitable reflector 22' which need not entirely obscure the lamp-globe but may be so constructed as to permit a ready circulation of air and a generous distribution of the light.

45 It will be observed that by the means described the lamp is permanently and substantially supported in a position closely in rear of and alongside the horizontal portion 3' of the bracket-arm and well to one 50 side of the needle-bar supporting head 4 and the vertical plane through the line of feed of the machine. The light from the lamp 22 will fall obliquely upon the work from the operator's right and will illuminate that 55 edge of the presser-foot relative to which the edge of the work is customarily guided. This disposition of the light avoids the casting of objectionable shadows upon the work by machine parts carried by or forming a 60 part of the bracket-arm. Also the lamp will not be subjected to excessive vibration since it is rigidly mounted adjacent the standard 3 or vertical member of the bracket-arm, rather than at the free end of 65 the latter, and the socket 14 is very close to

the point of support of the attachment on the sewing machine frame. Further, the device is permanently located within the vertical planes defined by the side and end edges of the bed 2 and within the external, 70 rearwardly projected outline of the gooseneck, as viewed from the front of the machine, whereby such device does not interfere with and need not be shifted to permit the dropping of the head within the cavity of 75 the usual drop-head cabinet, or with the placing of the cover of a hand-carrying case over the head.

The plate 11 is preferably provided with a laterally extending stop-lug 23 which is 80 bent in from the edge of the cover-plate proper and is adapted to strike externally the rim of the seat for the cover-plate and prevent sagging of the lamp below its normal operative position.

85 The lamp is so located as to be substantially invisible to the operator of the machine; the horizontal portion of the gooseneck effectively shielding the eyes of the operator from the glare of the lamp. As before stated, this location of the lamp permits the use of a rather shallow reflector which need not so fully envelop the lamp-globe as would otherwise be necessary if the reflector alone was depended upon to shield 90 the eyes of the operator from glare. The use of a shallow reflector is also desirable since it permits a ready circulation of air around the lamp globe and avoids overheating. Further, it permits ready removal and 100 replacement of the lamp globe.

95 While it is desirable with certain types of sewing machines to use the cover-plate as a support for the light, it is to be understood that the supporting element may assume other specific forms within the scope and without a sacrifice of the advantages of the invention, in its broader aspects.

Having thus set forth the nature of the invention, what I claim herein is—

110 1. The combination with a sewing machine frame having a bed and gooseneck including a standard and overhanging horizontal arm terminating in a head, together with the usual stitch-forming and feeding mechanisms, of an electric lighting device including a lamp-bulb and lamp-socket directly mounted horizontally closely in rear of and alongside the horizontal member of the gooseneck and intermediate the standard and head of the gooseneck, said socket being supported by a connection with said gooseneck.

115 120 125 2. The combination with a sewing machine frame having a bed and gooseneck, together with the usual stitch-forming and feeding mechanisms, of a lighting device including an electric lamp-socket and lamp disposed horizontally closely in rear of and alongside the horizontal member of the 130

gooseneck and well to the gooseneck side of the line of feed of the machine, and supporting means connecting said socket to said gooseneck adjacent the bend of the latter.

3. The combination with a sewing machine frame having a bed and gooseneck including a standard and horizontal arm terminating in a head, together with the usual stitch-forming and feeding mechanisms, of a lamp-support connected to said gooseneck adjacent the bend of the latter, and an electric lamp-socket and lamp-bulb non-adjustably connected to said support

10 15 and permanently located horizontally closely in rear of and alongside the horizontal member of the gooseneck between the standard and head of the gooseneck.

4. The combination with a sewing machine frame having a bed and gooseneck, together with the usual stitch-forming and feeding mechanisms, of a lighting device including an electric lamp-socket and lamp disposed horizontally closely in rear of and 20 25 alongside the horizontal member of the gooseneck and well to the gooseneck side of the line of feed of the machine, and supporting means connecting said socket to said gooseneck adjacent the bend of the latter, said supporting means being disposed entirely within the rearwardly projected external outline of the gooseneck as viewed 30 35 from the front of the machine.

5. A lighting attachment for sewing machines comprising a cover-plate adapted to close the usual opening at the rear of a sewing machine bracket-arm, and an electric lighting socket directly mounted on said cover-plate in close proximity to the latter, substantially as and for the purposes 40 45 specified.

6. A lighting attachment for sewing machines comprising a cover-plate adapted to close the usual opening at the rear of a sewing machine bracket-arm, said plate be-

ing formed with a lateral ear transverse to the plane of the plate proper, and an electric lighting socket secured to said ear in close proximity to the latter, whereby, when the attachment is secured over the opening 50 in the sewing machine frame, the said socket and the lamp carried thereby will be located in rear of the horizontal portion of the sewing machine bracket-arm and well to one side of the vertical plane through the line 55 of feed of the machine.

7. A lighting device for sewing machines comprising, a support adapted for attachment to a sewing machine gooseneck adjacent the bend of the latter and having a 60 horizontal aperture, an electric lamp-socket and lamp-bulb substantially in line with the axis of said aperture, and means for directly connecting said lamp-socket to said support, said connecting means including an element 65 horizontally entering said aperture.

8. A lighting attachment for sewing machines comprising, a cover-plate adapted to close the usual opening at the rear of a sewing machine gooseneck, said plate being 70 formed with a horizontally apertured projection transverse to the plane of the plate proper, an electric lamp-socket secured to said projection in close proximity to the latter, and securing means horizontally entering 75 the aperture in said projection.

9. A lighting attachment for sewing machines comprising, a sheet-metal cover-plate adapted to close the usual opening at the rear of the sewing machine bracket-arm, a 80 stop-lug bent forwardly from the plane of the cover-plate proper at the edge of the latter, an ear bent rearwardly from the plane of said plate at the edge of the latter, and an electric lighting socket fixedly mounted 85 upon and in close proximity to said ear.

In testimony whereof, I have signed my name to this specification.

FREDERICK DIEHL.
